UNITED STATES PATENT OFFICE.

FREDERICK A. OBERHEU, OF DETROIT, MICHIGAN.

DESIGN FOR A TIRE.

53,931.

Specification for Design.

Patented Oct. 7, 1919.

Application filed June 23, 1919. Serial No. 306,260. Term of patent 14 years.

To all whom it may concern:

Be it known that I, FREDERICK A. OBERHEU, a citizen of the United States, residing at Detroit, in the county of Wayne and State of Michigan, have invented a new, original, and ornamental Design for a Tire, of which the following is a specification, reference being had to the accompanying drawing, forming part thereof.

Figure 1 is a plan of a portion of a tire, showing my new design, and

Fig. 2 is a cross sectional view of the same.

I claim:

The ornamental design for a tire, as shown.

FREDERICK A. OBERHEU.

Witnesses:

THOMAS F. MURPHY,
KARL H. BUTLER.
